PLAY BOARD FOR A GAME

Joseph P. Mannina, 853 N. 5th St.,
San Jose, Calif. 95112

Filed Apr. 7, 1972, Ser. No. 242,286

Term of patent 14 years

Int. Cl. D21—01

U.S. D34—5 SS

FIG. 2

FIG. 3

FIG. 4

FIG. 5

FIG. 6

FIG. 1 is a top plan view of a play board for a game showing my new design therefor;

FIG. 2 is an edge elevation of FIG. 1 as seen from line 2—2 therein;

FIG. 3 is an edge elevation of FIG. 1 as seen from line 3—3 therein;

FIG. 4 is a perspective view of the play board for a game as shown in FIG. 1, the lower lefthand corner of the latter being foremost in this view;

FIG. 5 is an edge elevation of FIG. 1 as seen from line 5—5 therein; and

FIG. 6 is an edge elevation of FIG. 1 as seen from line 6—6 therein.

I claim:

The ornamental design for a play board for a game, as shown and described.
